UNITED STATES PATENT OFFICE.

JOHAN ALFRED SVENSSON, OF WASHINGTON, DISTRICT OF COLUMBIA.

BED-PLATE MOTION FOR PRINTING-PRESSES.

SPECIFICATION forming part of Letters Patent No. 730,174, dated June 2, 1903.

Application filed April 18, 1902, Serial No. 103,611. (No model.)

To all whom it may concern:

Be it known that I, JOHAN ALFRED SVENSSON, a citizen of the United States, residing at Washington, in the District of Columbia, have invented new and useful Improvements in Bed-Plate Motions for Printing-Presses, of which the following is a specification.

My invention relates to improvements in reciprocating bed-motions for roller printing-
10 presses; and the object of the same is to construct a simple and efficient device of this character which will reverse the bed by positive movement.

The novel construction used by me in carrying out my invention is fully described in this specification and claimed and illustrated in the accompanying drawings, forming a part thereof, in which—

Figure 1 is a longitudinal section on the line 1 1, Fig. 2. Fig. 2 is a transverse section on the line 2 2, Fig. 1. Fig. 3 is a detail of the cross. Fig. 4 is a detail of a toggle. Fig. 5 is a detail elevation of one abutment and the cross. Fig. 6 is a detail plan of the catch and cross.

Like numerals of reference designate like parts in the different views of the drawings.

My press is supported on two parallel side frames 1 of appropriate shape. A horizontal bed 2 is mounted on rollers 3, journaled on stud-shafts 4, seated in the apertures in the frames 1. Mounted on the upper surface of the bed 2 and on each side thereof is a rack-bar 5, which extends about two-thirds of the length of the bed. An impression-cylinder 6 is mounted transversely the frames 1 and bears two gears 7, located to mesh with the racks 5 to drive the bed 2. The cylinder 6 is keyed on a shaft 8, which is journaled in bearings 9, carried by vertical slides 10, mounted in guides 11, formed in the frames 1. Means for operating the slides to raise the cylinder 6 to raise the gear 7 clear of the racks 5 is provided by a pair of toggles 13, operated by cams 14. There are two pairs of the toggles 13, one pair on each side of the machine. The upper toggles 13^a are pivoted to the frames 1, while the lower toggles 13^b are pivoted to ears 10^a, formed on the slides 10. Rollers 15 are journaled on

the hinge-pins 16, which couple the toggles 13 together, and these rollers 15 are located to be engaged by the before-mentioned cams 14, which are carried by a shaft 17, journaled in bearings 18, carried by the slides 10. Enlarged apertures 19 permit a vertical movement of the shaft 17. By the above-described arrangement the slides 10 are reciprocated at every revolution of the shaft 17 and retain their elevated position during about one-half of the period of revolution of said shaft. A large gear 20 is keyed on the shaft 17 and meshes with a smaller gear 21, which meshes in turn with a gear 22, which meshes with a gear 23, keyed on the cylinder-shaft 8. The gears 21 and 22 are carried by stud-shafts 24 and 25, respectively, which are rigidly mounted in the slide 10. It is easily seen that the motion of the shaft 17 is communicated to the cylinder 6, which in turn drives the bed 2 through the medium of the gears 7 and racks 5.

To drive the bed 2 while the gears 7 are disengaged, a gear 26 is located beneath the bed 2 and in position to engage a rack 27, rigidly mounted on the bed. The gear 26 is keyed on a shaft 28, journaled in boxes 29^a and 30^a, carried by bracket-arms 29 and 30, respectively. The arms 29 and 30 are secured to a cross-bar 31, connecting the two slides 10 and constructed to move in unison therewith. The rack 27 does not extend the whole length of the bed 2, but spaces 32 intervene between the ends of the bed and the ends of the rack.

Keyed on the end of the shaft 28 is a disk 33, bearing a crank-pin 34, which bears a sliding rectangular block 35, which is slidably mounted in parallel guides 36, formed on the vertical arms 37 of a cross 38. The cross 38 comprises the vertical arms 37 and two horizontal arms 39, which are slidably mounted in guides 40, formed in the head of a standard 41, rigidly connected to a cross-bar 42, connecting the two frames 1. Abutments 42 are formed on the bed 2, one on each end, and are located to be engaged by the upper arm 37 on the cross 38 to reverse the bed. Rounded lugs 44 are formed on the cross 38 in position to be engaged by gravity-catches 45,

carried by the abutments 43. The catches 45 have rounded heads 45^a and rounded noses carrying rollers 45^b to adapt them to ride over the lugs 44. A stop 46 is carried by the guides 5 40 and serves to hold the catch down to prevent its releasing its hold on the lug 44 until either one of the gears 7 or 26 engages its respective rack 5 or 27 and drives the bed.

In operation the shaft 17 is driven from 10 some source of power. This motion will be communicated to the cylinder 6 through the intermediate gearing carried by the slide 10. When the press is in the position shown in Fig. 1, the toggles 13 are straightened out, 15 the slides 10 are in their lowermost position, and the gears 7 are in engagement with the racks 5. The bed 2 will then be traveling toward the left and will continue to do so until the gears 7 clear the ends of the racks 5.

20 When this position has been reached, the upper arm 37 of the cross 38 will be in contact with the right-hand abutment 43 and the catch 45 thereon will be in engagement with the corresponding lug 44. The gears are so proportioned and the crank-pin 34 so located that it is now in its lowermost position. The movement of the crank-pin 34 communicated to the cross 38 now controls the movement of the bed 2 and will continue to do so for one-half revolution of the crank-shaft—that is, until the crank reaches its highest position. During this one-half revolution of the crank-pin the stop 46 prevents catch 45 from releasing its hold, and thus locks cross 38 and bed 35 2 together. Also during the before-mentioned one-half revolution of the crank-shaft the cam 14 and toggles 13 operate the slides 10 and raise the gear 26, so it can engage rack 27. The gear 26 now drives the bed 2 for 40 one complete revolution. The crank-pin 34 is now again at its highest position and assumes control of the bed for another half-revolution. During this one-half revolution the cylinder is again lowered and gear 7 engages rack 5, when the cycle will be repeated. The shape of the nose on the catch 45 allows 45 it to be pulled over the lug 44 when the roller 45^b is clear of the stop 46, and thus release its hold of the cross 38.

50 I do not wish to be limited as to details of construction, as these may be modified in many particulars without departing from the spirit of my invention.

Having thus described my invention, what 55 I claim as new, and for which I desire to secure Letters Patent, is—

1. In a bed-motion for printing-presses, the combination with a bed mounted to be reciprocated and bearing a rack, of vertical slides 60 mounted in the frame of the press, a crank-shaft journaled in said slides, a cross bearing guides engaged by the crank-pin on said crank-shaft, said cross being mounted to be reciprocated by said crank to engage said bed to reverse its movement, a gear mounted

on said shaft and located to be brought into engagement with said rack, and means for operating said slides to bring said gear into engagement with said rack and to disengage it therefrom, substantially as described. 70

2. In a bed-motion for printing-presses, the combination with a bed mounted to be reciprocated, of vertical slides, an impression-cylinder journaled in said slides and bearing a gear, a rack mounted on said bed and located to be engaged by said gear, a shaft journaled in said slides and bearing a gear, a rack mounted on said bed and located to be engaged by said last-mentioned gear, and means for intermittently operating said slides, substantially as described. 75

3. In a bed-motion for printing-presses, the combination with a bed mounted to be reciprocated, of a rack mounted on the upper side of said bed, an impression-cylinder carrying 85 a gear located to be thrown into mesh with said rack, slides mounted in guides and supporting said impression-cylinder, a crank-shaft bearing a gear, and supported by said slides, a rack mounted on the under side of 90 said bed and in position to be engaged by said last-mentioned gear, abutments mounted on the ends of said bed, a cross mounted in guides and positioned to engage said abutments, and means for operating said slides, 95 substantially as described.

4. In a bed-motion for printing-presses, the combination with a bed mounted to be reciprocated, a rack mounted on the under side of said bed, a rack mounted on the upper side 100 of said bed, vertical slides, means for operating said slides, an impression-cylinder mounted in said slides and bearing a gear located to mesh with said rack mounted on the upper side of said bed, a shaft carried by said 105 slides and bearing a crank and a gear located to mesh with said first-mentioned rack, a slidingly-mounted cross engaged by said crank to drive said cross to reverse said bed, and means for driving said shaft, substantially as described. 110

5. In a bed-motion for printing-presses, the combination with a bed mounted to be reciprocated, a rack mounted on the upper side of said bed, a rack mounted on the under side 115 of said bed, vertical slides, an impression-cylinder carried by said slide and bearing a gear, a crank-shaft carried by said slides and bearing a gear, means for intermittently operating said slides to engage said gears and said racks, means for driving said impression-cylinder and said shaft, and means for reversing said bed which means is operated by said crank, substantially as described. 120

6. In a bed-motion for printing-presses, the 125 combination with a bed mounted to be reciprocated, a rack mounted on the under side of said bed, vertical slides mounted to be moved in unison, a shaft bearing a crank and gear, said shaft being carried by said slides, a cross 130

mounted to be reciprocated and having guides formed therein which are engaged by said crank, means for operating said slides to engage and disengage said rack and said gear, and means for driving said gear to drive said bed and to reciprocate said cross to reverse the motion of said bed, substantially as described.

In testimony whereof I have hereunto set my hand in presence of two subscribing witnesses.

JOHAN ALFRED SVENSSON.
